CLAIM

The ornamental design for a rechargeable in the ear hearing amplifier, as shown and described.

DESCRIPTION

FIG. 1 is a top perspective view of the embodiment of the present design;

FIG. 2 is a bottom perspective view of the embodiment of the present design;

FIG. 3 is a bottom plan view thereof;

FIG. 4 is a top plan view thereof;

FIG. 5 is a rear elevation view thereof;

FIG. 6 is a front elevation view thereof;

FIG. 7 is a first side elevation view thereof; and,

FIG. 8 is a second side elevation view thereof.

The broken lines in drawing views are included for the purposes of illustrating the unclaimed portions of the claimed design.
